UNITED STATES PATENT OFFICE.

CLAIR D. LAKE, OF BINGHAMTON, NEW YORK, ASSIGNOR TO THE TABULATING MACHINE COMPANY, OF ENDICOTT, NEW YORK, A CORPORATION OF NEW JERSEY.

RELAYLESS COUNTER.

Original application filed June 17, 1922, Serial No. 539,078. Divided and this application filed June 28, 1924. Serial No. 722,972.

To all whom it may concern:

Be it known that I, CLAIR D. LAKE, a citizen of the United States of America, residing at Binghamton, in the county of Broome and State of New York, have invented certain new and useful Improvements in Relayless Counters, of which the following is a full, clear, and exact description.

10 This invention relates to improvements in tabulating apparatus, and more particularly to improvements in the record card circuit, the controlling means therefor and the controlled magnet circuit as were heretofore of the type employed in electric tabulators 15 shown in Hollerith Patent No. 945,236 and Lake Patent No. 1,307,740.

The circuits commonly and generally used in tabulating apparatus may be subdivided 20 into two general classes. In one construction, which is the above Hollerith Patent, as an example, the record card circuit controls the energization of the counter magnet and the establishment of its circuit. After 25 the circuit is initially energized the record card circuit is shunted by a suitable relay or other means so that arcing at the index point perforations is obviated by materially cutting down the flow of current in the card circuit. During these periods the magnet 30 circuit is maintained only to be finally interrupted by a supplemental circuit controller or contact device.

In other constructions, of which the Lake 35 Patent is an example, the card circuit initiates the energization of the magnet and the establishment of the circuit. Immediately thereafter both the card circuit and the magnet circuit are automatically broken, 40 and at the end of the cycle the magnet circuit is reestablished leaving the parts in proper condition for a new cycle upon the next closure of the card circuit. This arrangement prevents arcing at the card since 45 the card circuit is broken and no current is flowing at the time the brush leaves the index point perforation in the card.

In certain types of tabulating apparatus 50 it is desirable to maintain the flow of current in magnet circuits during a part of the card cycle as in the Hollerith construction. It is also desirable to prevent arcing at the brushes and this may be effected by provid-

ing means for shunting the card circuit and at the same time maintaining the magnet 55 circuit.

The present invention is directed to the provision of a simple arrangement of circuits and controlling devices therefor which will provide for the shunting of the card circuit and for maintaining the magnet circuit without the necessity of employing supplemental relays for shunting the card circuit.

Other and more detailed objects of the present invention will be hereinafter pointed out in the accompanying specification and claims and shown in the drawings which show by way of illustration a preferred embodiment of the invention.

In the drawings,

Fig. 1 shows a diagrammatic view of a conventional tabulating apparatus embodying the invention.

Fig. 2 is an enlarged detail of one counter and its associated controlling contacts.

Figs. 3 and 4 are detail views showing different forms of record card circuit controllers embodying balls for the contacts.

In Fig. 1 of the drawings, 10 designates a stack of record cards which are fed by the usual upper and lower feed rolls 11 and 12 past cooperating brushes 13 and contact blocks 14. If desired, the index point circuit controlling means may be of the form shown in Figs. 3 and 4. Here metallic balls are used to make the contacts through the index point perforations in the cards. In Fig. 3, two balls are provided, each being pressed into contact by means of spring 16. The contact block 14^a is suitably recessed to receive one of these springs and the common brush holder bar 17^a is recessed to receive the other. Fig. 4 illustrates a similar construction except that one of the balls 15 is eliminated and contact is made directly with contact block 14. These devices are adapted to establish the card circuit when an index point perforation comes under the ball or balls.

The gearing for rotating the feed rolls is 100 shown conventionally at 18 in Fig. 1. This gearing receives its drive from a shaft 20 which by a belt and pulley connection is driven by tabulator motor 21. A shaft 22 forms the main drive shaft of the tabulator 105 and is shown broken away in the upper part.

of Fig. 1 and extended into cooperation with two tabulator counters in the lower part of the figure. A similar shaft 23 driven in unison with the card feeding devices carries a number of cams for operating certain contact devices as will be hereinafter described. The card feeding section of the machine is provided with the usual card lever 24 which closes card contacts 25 when cards are passing under the brushes.

To start the tabulator into operation the operator first closes main line switch 26 to the supply main. Thereafter start key 27 is depressed which, upon the closure of its contacts, establishes a circuit from line 28 through start key 27, motor relay magnet 29, stop key 30, tabulator motor 21, and back through wire 30, etc., to source. The energization of motor relay magnet 29 establishes a holding circuit for the tabulating motor 21 through the armature of motor relay magnet 29, line 31, through cam contacts 32 which are closed after the motor has rotated the parts, thence back through wire 28 to source. Cards now pass downwardly through the feed rolls and close the card contacts 25. Cam contacts 33, 34 are make and break cams generally used in tabulating apparatus and serve to establish a circuit 35 to the card lever contacts 25 and to interrupt this circuit once per card cycle. The closure of the card lever contacts 25, when circuit 35 is established, energizes counter control relay magnet 36 and motor control relay magnet 37, current flowing from these magnets back to source. The attraction of the armature of motor control relay 37 establishes another holding circuit for the tabulating motor 21 through a line 38 and thence through motor relay 29 and through the rest of the circuit as previously traced. This holding circuit maintains the machine in operation when cam contacts 32 break once per card cycle. The purpose of the contacts 32 is to interrupt the tabulating operation upon deenergization of motor control relay 37 after the last card has passed through the machine and permitted contacts 25 to open.

The energization of counter control relay 36 attracts its armature and closes a circuit 40 supplied from the make and break cam contacts 34, 33. From wire 40 current flows through the armature of relay 36 thence through line 41 to the common brush bar 17 or 17^a. Current also flows through a line 42, the purpose of which will hereafter be described.

It will be assumed that an index point perforation in one of the record cards 10 which has come under one of the controlling brushes or its equivalent ball contact and permitted current to flow through one of the lines 43 or 43^a, forming part of the card circuit, and through the plug connections to

the corresponding counter magnet 44. The energization of the counter magnet 44 will attract its armature 45 which serves as a latch for clutch lever 46 and permit this clutch lever to swing counterclockwise under the influence of the resiliency of blade spring 47. The movement of the clutch lever is independent of the energization of magnet 44, but is controlled thereby through latches 45. This movement of the clutch lever causes the clutch member 48 to engage its complementary clutch member whereupon the counter wheel 49 is rotated in the usual manner of a Hollerith counter. The swinging to the right of blade 47 will also allow contacts 50 to close and establish a direct shunt circuit from line 42 through the counter magnets 44. This circuit thus establishes shunts the card circuit and prevents arcing at the record card circuit controller when the brushes or their corresponding ball contacts leave the perforations in the cards. This circuit also maintains counter magnets energized during the remainder of the adding cycle, then break cam 34 opens circuits. The parts just described take the place of the relays heretofore used in counters of the Hollerith type. At the completion of the adding cycle a suitable cam 51 displaces a knock-off bar 52 and restores the clutch lever permitting the same to be relatched by the armatures 45 and disengages the counter wheel or wheels from the constantly rotating drive shaft, also opens contacts 50.

The foregoing description has described the operation of the counter unit shown to the left in Fig. 1. The description of the modified circuit controller shown in cooperation with the counter unit to the right in Fig. 1 need not be here given as it forms the subject matter of a copending application, Serial No. 569,078, filed June 17, 1922, of which the present application is a division. The aforesaid parent application also covers generically both forms of circuit controllers, namely, the embodiments shown in cooperation with both the left and right hand counter units in Fig. 1.

The subject matter directed to the ball contact devices is not herein claimed as it forms the subject matter of another copending application, Serial No. 672,333, filed November 2, 1923.

What I claim is:

1. In a tabulating apparatus, the combination with a record card having an index point, of a record card circuit and a magnet circuit, circuit controllers in said circuits, one of said controllers being operated by the record card to establish both the card circuit and the magnet circuit, a magnet in said magnet circuit, means controlled by said magnet and comprising one of aforesaid circuit controllers which is operable inde-

pendently of the energization of the magnet for shunting the card circuit and for maintaining a flow of current in the magnet circuit.

2. In a tabulating apparatus, the combination, with a record card having an index point, of cooperating record card and magnet circuits, a record card actuated circuit controller in the circuit and a controlling magnet in its circuit, means for energizing said magnet and establishing its circuit upon the closure of the card circuit, means controlled by the magnet circuit by operable independently of the magnet for rendering the card circuit ineffective and for preventing arcing at the record card circuit controller, said last mentioned means having provisions for concurrently and subsequently maintaining a flow of current in the magnet circuit.

3. In an apparatus of the kind described, in combination with counter wheels and controlling magnets, of a record actuated circuit controller of circuits including said magnets and said controllers, of shunt circuits through said magnets adapted when

established to shunt the record actuated circuit controllers out of the aforesaid circuits, and circuit controllers for said last mentioned shunt circuits adapted to be operated by means controlled by the counter magnet but operable independently thereof.

4. In a counter of the kind described, the combination of counter wheels or corresponding electro magnets and intermediate clutch levers for effecting the proper movements of said counter wheels, armature for said magnets normally latching said clutch levers out of operation, spring actuated means for moving said clutch levers, and contact devices associated with said means adapted to be actuated upon the unlatching of the clutch levers, a record card controlled circuit for initially energizing the counter magnets, a supplementary circuit including said contacts adapted to shunt the record card controlling means out of circuit and to maintain in circuit the counter magnets during the adding cycle.

In testimony whereof I hereto affix my signature.

CLAIR D. LAKE.
